UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO PREVENT ROTATION OF BOBBINS.

Application filed May 4, 1925. Serial No. 27,641.

This invention relates to improvements in multi-color weft replenishing mechanism for looms and an object of the invention is to prevent rotation of bobbins on their axes in such mechanism as they await transfer into an exhausted shuttle.

In multi-color weft replenishing mechanism of the usual type the bobbins are arranged in parallel vertical stacks and are released one at a time to move from a selected stack to a common transfer position. It is found that the vibration of the loom causes the bobbins to rotate on their axes so as to twist the end of the filling extending from the thread holder resulting in breakage of the filling at the time of transfer. In my co-pending application Serial No. 702,415 there is shown a pivoted wall between adjacent stacks of bobbins normally held against the bobbins to prevent vibration thereof. At indication of weft exhaustion the wall is moved to bobbin releasing position and immediately returned to bobbin restraining position irrespective of the length of time lapsing between the indication of weft exhaustion and the subsequent transfer. This interval of time may be several picks, during which it is desirable that the bobbins be restrained but in the mechanism set forth in said application the bobbins are released for a short length of time only and it is the principal object of my present invention to provide a somewhat longer time for the releasing of the bobbins without requiring them to remain unrestrained until transfer.

It is a more particular object of my invention to provide an auxiliary slide actuated by the color selector of the weft replenishing mechanism and held in both extreme positions by means of a toggle and spring, the auxiliary slide being returned to normal bobbin restraining position positively by the regular oscillation of the color selector.

With these and other objects in view which will appear as the description proceeds, my invention resides in the combination and arrangement of parts hereinafter described and set forth in the claims.

In the accompanying drawings wherein a convenient embodiment of my invention is illustrated,

Fig. 1 is a side elevation of a multi-color weft replenishing mechanism having my invention applied thereto as viewed from the central portion of the loom, 55

Fig. 2 is a horizontal section taken on line 2-2 of Fig. 1,

Fig. 3 is a vertical section taken on line 60 3-3 of Fig. 1,

Fig. 4 is a view similar to Fig. 2 but showing the parts in a different position, and

Fig. 5 is a detail view similar to Fig. 1 65 showing the upper end of the auxiliary slide 65 and the toggle as they appear when in raised position.

Referring more particularly to the drawings it will be seen that I have provided a weft replenishing frame 10 on which is 70 guided for longitudinal and angular motion a shaft 11 having secured thereto a color selector 12 which is provided with a plurality of fingers 13. Said fingers are movable longitudinally with the shaft 11 and are moved 75 angularly in two directions from the position shown in Fig. 3, the downward motion being regular and occurring every second pick when the shuttle is on that side of the loom opposite the replenishing mechanism 80 and the up motion occurring only at indication of weft exhaustion when the shuttle is on the weft replenishing side of the loom by means of link 14 and lever 15 shown in 85 Fig. 1. Guided for vertical movement on the frame 10 is a plurality of upright slides 16 each of which is provided with upper and lower lugs 17 and 18, respectively, positioned for engagement with one or the other of the fingers 13.

The frame 10 is provided with stationary walls 19 and has pivotally mounted thereon walls 20 which cooperate with adjacent walls 19 to define vertical compartments for the heads of the bobbins. At indication of substantial weft exhaustion the slide 16 corresponding to the active shuttle will be raised to give the lowermost bobbin of the associated stack or compartment its initial movement toward transfer position. The slide 100 16 will remain raised until the indicating shuttle again arrives under the replenishing mechanism at which time said slide is restored to normal down position to give the bobbin its second and final movement toward transfer position. The matter thus 105

far described, with the exception of the pivoted walls 20, is substantially the same as set forth in Patent No. 1,030,748.

The device for actuating the walls 20 comprises an auxiliary slide 30 movable between fixed guides 31 and has a foot 32 formed therewith and extending over the fingers 13. The upper end of the slide 30 has pivotally connected thereto as at 33 a pair of links 34 through which pass studs 35 secured to and extending from the walls 20. Said links 34 are normally out of alignment and angularly disposed with respect to each other substantially as shown in Fig. 1, being held in this position by a tension spring 36 hung between the studs 35. Stop screws 37 and 38 on the slide 30 engage the lower and upper guides 31, respectively to limit movement of said slide. Said spring 36 normally holds the walls 20 as shown in Fig. 2 in bobbin restraining position and at indication of substantial weft exhaustion the slide 30 will be raised to rock the walls 20 to bobbin releasing position. This portion of the device is substantially the same as that set forth in said co-pending application Serial No. 702,415.

As previously stated the device set forth in the aforesaid application permits the slide 30 to remain in raised position for a comparatively short time only, said slide moving down with the finger 13. In order to provide a short dwell in the motion of the slide 30 to afford more time for the dropping of the bobbins, I arrange the links 34 so that the pivot 33 will pass slightly above the line joining the studs 35 as the finger 13 approaches the end of its upward travel so as to hold the parts in the bobbin releasing position shown in Figs. 4 and 5. On the following pick the fingers 13 will be given their regular downward motion at which time one or the other of them will engage the lower foot 39 of the slide 30 to depress the same and restore it to normal position with the walls 20 in bobbin restraining position. In the aforesaid application a separate finger is secured to the shaft 11 but I have found that the usual fingers 13 can be employed to move the slide 30 inasmuch as one of said fingers will always lie between said auxiliary slide and the adjacent slide 16.

From the foregoing it will be seen that I have provided means for normally restraining vibration of the bobbins and for temporarily removing the strain for approximately one pick of the loom at the time of indication of weft exhaustion, the interval during which the bobbins are released being entirely independent of the number of picks lapsing between the indication of exhaustion and the subsequent transfer but being longer than the comparatively brief interval during which the selec-

tor fingers 13 are in raised position. It will also be seen that the toggle connection afforded by the links 34 provides for holding the walls in bobbin releasing position until the subsequent pick, the movement of the walls 20 toward bobbin restraining position as the pivot 33 passes above the line of the studs 35 being negligible and insufficient to interfere with the descent of the bobbins. It will also be seen that said auxiliary slide is raised and lowered by the usual fingers of the color selector.

Having thus described my invention it will be apparent that changes and modifications may be made therein by those skilled in the art without departing from the spirit and scope of the invention, and I do not wish to be limited to the details herein disclosed but what I claim is:

1. In a device to prevent rotation of bobbins in weft replenishing mechanism, a bobbin compartment, a controller to regulate the delivery of bobbins therefrom, a bobbin restraining device normally preventing rotation of the bobbins, an angularly movable actuator having a movement in one direction on an indicating pick of the loom to move the controller and also to engage the device and move the same to bobbin releasing position, and a retainer for the device to hold the latter in bobbin releasing position independent of the angularly movable actuator, said actuator having a second regularly recurring movement in the opposite direction to engage the device and restore the same to bobbin engaging position on a non-detecting pick of the loom.

2. In a device to prevent rotation of bobbins in weft replenishing mechanism, a bobbin compartment, a controller to regulate the movement of bobbins from the compartment, a bobbin restraining device normally engaging the bobbins to prevent rotation thereof and movable to bobbin releasing position, an actuator movable from normal position upon indication of weft exhaustion to move the device to bobbin releasing position and returnable immediately thereafter to normal position, and means independent of the controller and operable by the actuator on the next pick of the loom to return the device to bobbin restraining position.

3. In a device to prevent rotation of bobbins in weft replenishing mechanism, a bobbin compartment, a controller to support and regulate the delivery of bobbins from the compartment, a restraining device normally acting to restrain vibration of the bobbins, means operable upon indication of weft exhaustion to move the controller and the restraining device to release the bobbins, and a retainer acting independently of the means to hold the restraining device in bobbin releasing position, said means having a subsequent periodic movement to engage the

retaining device and restore the same to bobbin restraining position.

4. In a device to prevent rotation of bobbins in weft replenishing mechanism, a bobbin compartment, a controller to regulate the delivery of bobbins from the compartment, a restraining device normally in engagement with the bobbins to prevent rotation thereof, an actuator to move the controller and device simultaneously to release the bobbins, means to hold said device in bobbin releasing position for one pick of the loom, and means acting thereafter and independently of the controller to restore the restraining means to bobbin engaging position.

5. In a device to prevent rotation of bobbins in weft replenishing mechanism, a bobbin compartment, a bobbin restraining device normally engaging the bobbins in the compartment to prevent rotation thereof, a controller to regulate the delivery of bobbins from the compartment, an actuator to move the controller and device to bobbin releasing position simultaneously, a retainer independent of said actuator to hold the device in bobbin releasing position for one pick of the loom, and means acting thereafter independently of the controller to return the device to normal bobbin engaging position.

6. In a weft replenishing mechanism for looms, a bobbin compartment, a controller to regulate the delivery of bobbins from the compartment, a device acting normally to restrain rotation of the bobbins while in the compartment, an actuator to simultaneously move the device to remove the restraint from the bobbins and actuate said controller, and means acting independently of the controller and moved by the actuator to return said restraining device to normal position after a delay of one pick.

7. In a device to prevent rotation of bobbins in weft replenishing mechanism, a plu-

rality of pairs of bobbin compartments, a movable wall for each pair of compartments, an actuator movable at indication of weft exhaustion, controlling means for the walls, and links defining a toggle connecting said controlling means and said walls, said actuator adapted to move the toggle past the center thereof to hold the controlling means and walls in bobbin releasing position independently of the position of the actuator.

8. In a device to prevent rotation of bobbins in weft replenishing mechanism, bobbin compartments, controllers movable to regulate the delivery of bobbins from the compartments, devices to restrain rotation of the bobbins, said devices being effective to release as well as restrain the bobbins, means to move the devices out of bobbin restraining position as the controllers move, holding means to retain the devices out of bobbin restraining position temporarily, and means acting on the holding means to overcome the effect of the latter to return the devices to bobbin restraining position after one pick independently of the control means.

9. In a device to prevent rotation of bobbins in weft replenishing mechanism, a plurality of bobbin compartments, a controller for each compartment to regulate the movement of bobbins, an angularly and longitudinally movable actuator for the controllers having fingers to engage one of the controllers at a time, and a device to prevent rotation of the bobbins in the compartments having a portion operatively positioned with respect to one or the other of said fingers in all longitudinal positions of the actuator to be moved to bobbin releasing position as the actuator moves angularly in any longitudinal position thereof.

In testimony whereof I have hereunto affixed my signature.

WALTER H. WAKEFIELD.
